UNITED STATES PATENT OFFICE.

HENRY H. BLISS, OF WASHINGTON, DISTRICT OF COLUMBIA.

ROCK OR COAL DRILLING OR OTHER MACHINE.

SPECIFICATION forming part of Letters Patent No. 636,748, dated November 14, 1899.

Original application filed December 24, 1886, Serial No. 222,524. Divided and this application filed August 6, 1895. Serial No. 558,408. (No model.)

To all whom it may concern:

Be it known that I, HENRY H. BLISS, a citizen of the United States, residing at Washington, in the District of Columbia, have invented 5 certain new and useful Improvements in Rock or Coal Drilling or other Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a plan view of the principal 15 parts of a mechanism embodying my improvements. Fig. 2 is a front elevation showing also a frame of one of the forms that can be utilized to support the operative parts. Fig. 3 shows a section of the wheel-support, the 20 master-wheel being an inside view, together with the intermediate gearing. Fig. 4 is a longitudinal section of the shaft-advancing devices on a larger scale. Fig. 5 is a longitudinal section of the same taken on a horizontal plane looking upward. Fig. 6 is a diagrammatic view of the electric circuit. Fig. 7 is a partial section of the parts in Fig. 8. Fig. 8 is a cross-sectional view of the feed mechanism. Fig. 9 is a plan view of the 25 rotary motor on a larger scale.

A indicates a frame adapted to carry and support the operative parts. It is shown as mounted on an upright frame A' by means of trunnions *a* projecting outwardly from the 35 frame A. The upright frame A' is portable and of the class of those adapted to be fastened by jack-screws at the top and bottom, as is common in mining, quarrying, drilling, &c.

At the front of the frame there is arranged 40 the electric motor, (indicated as a whole by D,) it having the field-magnets at D', with the poles *d* and the armature D''. The armature is formed upon or secured to a tubular shaft 45 *d'*. This shaft has the pinion F secured to it, which drives an intermediate wheel F''. The latter engages with the main master-gear F⁵, which is internally toothed and is formed with a hub or hollow journal F⁶. The latter is

fitted in a bearing *d*³, formed on or secured 50 to the frame A. The tubular armature-shaft *d*' is preferably fitted over a projection *d*⁴ on this hub. At its opposite end it is supported on a bearing *d*².

B represents the driven shaft. As shown, 55 it is provided with a drill or boring cutter C, which may be of any of the ordinary forms used in mining or quarrying.

The shaft B is provided with two grooves 60 *b*₁, in which fit the gibbs *f*, that are loosely connected to the hub F⁶ of the master-wheel F⁵.

D⁸ indicates, more or less conventional, the commutator, brushes, and brush-holders for the armature.

As the present invention does not relate to 65 the well-known details of the parts of a motor adapted to attain my purposes and as they will be readily understood by those acquainted with such mechanisms, it is not necessary to illustrate or describe all of their parts. In 70 fact, the rotation-causing motor, its hollow armature-shaft, gearing, and adjuncts are illustrated in my other application, Serial No. 222,524, filed December 24, 1886, from which the present subject-matter was withdrawn; 75 but the present construction differs from that remaining in the said other application in important matters incident to the feeding devices. A threaded drill-shaft was therein shown and a threaded nut for moving it longitudinally. This nut was arranged so as to be adapted to yield if a very severe resistance should be met by the tool. In the present case I dispense with the threaded devices and effect the longitudinal motion of the tool-shaft 80 by electromagnetic action.

Q is a tube which is secured to the rear side of the motor or to the frame A, at the rear thereof. The tool-shaft extends backward into this tube. Around the shaft are placed 90 a series of spools, hollow coils, or solenoids H'. These also can be constructed and applied in any preferred way, and the number thereof can be varied as occasion requires. They are electrically connected with the current-supplying circuit in such way that they can be successively energized from one end 95 to the other of the series. At the rear end

of the shaft there is a core P, shown as being a cylindrical block situated within the tube Q and adapted to move freely therein. It is so related to the coils or solenoids H' that it will be drawn forward from one to the other successively as they are energized and will act to move the shaft longitudinally. As it advances it causes the current to be cut out from one or more coils and into one or more of the others successively, as follows:

h³ is a section of conductor in the tube Q, preferably supported on the insulation indicated by h. It is connected to the supply main through the conductor h', which passes out from the tube.

h⁴ h⁴ are a series of conductor-sections also supported by insulation within the tube Q, they being parallel to the conductor h³. Each solenoid or magnet H' has one terminal connected to one of the conductor-sections h⁴ and the other terminal connected to the outside circuit, as at r.

The core P is provided with contacts q⁴ and q⁵, these being preferably small rollers electrically connected to an insulated plate q⁶. The contact q⁴ bears against conductor h³, and the contact q⁵ is arranged to bear against the conductor-sections h⁴ successively.

When current is passing through h³ and h⁴, it goes through contact q⁴, plate q⁶, and contact q⁵ to a conductor h⁴, and thence through the coils of one of the magnets. Thereupon the magnet is energized and the core P is drawn toward it.

It will be seen that the sections h⁴ are somewhat behind their respective coils—that is, only partially overlap the coils. Therefore the contact q⁵ passes from each section h⁴ to the next just before the core P reaches the central or neutral position in each coil.

In order to hold the core P from rotating, I provide stay-rods Q', which permit it to slide longitudinally, but prevent it from turning.

The ends of the conductor-sections can be inclined as shown, so that the contact q⁵ can readily touch two of them simultaneously and prevent either the forming of an arc or the stoppage of the core.

The operation of the mechanism described will be readily understood, reference being had to the diagram of circuits in Fig. 6 in connection with the other figures. If the switch I be in the position shown in Fig. 6, the current will pass from the positive main through the switch and the conductor h' to the conductor h³, and thence (assuming that the feed-core P is in its rearmost position) through the contacts q⁴ q⁵ and the first conductor h⁴ and the first solenoid H' to the conductor r to the motor, and thence back to the switch and the negative main. Instantly the motor is put into rotation and it, through wheels F F' F⁵ and gibs f, rotates the shaft B, and at the same time the first solenoid H' is energized and the core P is drawn forward into it, resulting in a longitudinal advance of

the shaft B. As the core advances its contact q⁵ moves forward and ultimately passes from the first section h⁴ to the second, whereupon the current is cut out from the first coil H' and now passes through the second one, which, being in advance of the core, exerts a forward pull. This continues until the core has reached the front end of the tube or has traveled the desired distance. Then the switch is moved to cut the current from the machine either by hand or automatically. The shaft B and core P can, after the current is cut out, be readily pushed back by hand. To avoid imparting jars or blows to the rear end of tube Q, a cushioning-spring, as at Q², can be employed. At K, Fig. 7, there is indicated a trip by which the core can itself automatically actuate the switch. A feed mechanism of this sort obviates the necessity of the lever or equivalent, the divided nut, and the several parts connected therewith, which are necessary with the yielding feed devices in a mechanism of the other sort. The current itself is utilized through electromagnetism to effect both the rotation and the longitudinal movement of the shaft.

The parts indicated by I are merely intended for conventionally illustrating a switch or cut-out. Numerous devices have long been well known to electricians for cutting off current, reversing it, &c., either of which can be used. The advancing parts of the mechanism can be utilized to actuate the switch. Thus in Fig. 7 a trip is shown at H in the path of the core P. It can be placed at any suitable point in the tube Q.

I am aware of the fact that it has been proposed to employ solenoids for moving longitudinally a shaft for either of several purposes. Thus it has been proposed to mount the armature of an electric generator upon a shaft capable of a limited longitudinal movement and to connect with the core of a solenoid, arranged in a circuit including said generator, devices for moving said shaft in one direction or the other to bring the armature into alignment with a varying number of field-coils. Also it has been proposed to reciprocate a drill by means of a series of solenoids surrounding a core connected with the stem of the drill and to impart a slight rotation to such stem at the end of each forward or downward reciprocation. In the last construction the solenoids were electrically connected with two separate contact-plates arranged externally of the solenoids, and longitudinally movable pins were extended through the plates, separating the solenoids into the path of a cam on the core, whereby the said contact-plates connected with each solenoid would be successively forced together to cut out the current from the solenoid as the core moved longitudinally. But I believe myself to be the first to have combined with a shaft of the character of that at B both a continuously-rotating motor and an electric

motor for advancing it longitudinally while rotating, and the first to have combined with such a shaft a rotation-causing electromotor and a supplemental electric motor, such as a series of two or more solenoids for moving the shaft longitudinally, one terminal of each solenoid being connected with a conductor lying between the said shaft and the solenoids. By this construction the electric contacts for controlling the passage of current through the solenoids can be arranged within the series of solenoids.

I do not herein claim any of the matters claimed in my said other application, Serial No. 222,524, filed December 24, 1886, preferring to claim herein those which are incident to the use of solenoids or an electromagnetic motor (supplemental to the rotation-causing devices) for causing longitudinal movement of the shaft entirely by electromagnetism.

While I have shown the present improvements as being embodied in a machine for drilling, cutting, or mining coal or similar material, I do not wish to be limited thereto.

25 What I claim is—

1. The combination of a driven shaft, an electromotor for imparting rotary motion thereto having an armature mounted independently of said shaft, and a supplemental electromotor for moving the shaft longitudinally, it having a series of two or more electromagnets adapted to be successively brought into action, substantially as set forth.

2. The combination of the driven shaft, an

35 electromotor for imparting longitudinal movement to said shaft and having its armature mounted independently thereof, said motor having a series of two or more electromagnets adapted to be successively energized, and power devices supplemental thereto for imparting rotary motion to the shaft, substantially as described.

3. The combination of the driven shaft, means for continuously rotating it, a series 45 of two or more solenoids having a core arranged substantially as set forth to move said shaft from one end of its path longitudinally to the other, substantially as set forth.

4. The combination of the rotary driven 50 shaft, the electromotor for moving said shaft longitudinally, it having a series of two or more solenoids surrounding the shaft, and a core within said solenoids and engaging with said shaft and adapted to move from one to the other thereof and power devices actuated independently of the said electromotor for imparting rotation to the said shaft, substantially as set forth.

5. The combination with the rotary driven 60 longitudinally-movable shaft of two independent electromotors one for imparting rotary movement to the shaft and having its armature mounted independently thereof, and the other having a series of two or more mag-

nets adapted to propel the shaft by electromagnetic attraction, substantially as set forth.

6. The combination with the rotary driven longitudinally-movable shaft of the independent electromotors one for imparting rotary movement to the shaft and having its armature mounted independently thereof, and the other having a series of two or more magnets adapted to propel the shaft by electromagnetic action, substantially as set forth.

7. The combination of the shaft, the motor for rotating the shaft, a series of two or more solenoids placed around the shaft and acting independently of the said motor, the core adapted to travel from the interior of one 80 solenoid to the other to advance the shaft, and the interrupted or sectional conductor within the solenoids and electrically connected therewith, substantially as set forth.

8. The combination with the longitudinally-moving cutting-tool of the series of two or more solenoids around the longitudinal axis of the cutting-tool, the core within the solenoids connected to the cutting-tool, the electric contact within the interior of the 90 solenoids and carried by the core and the conductor within the said solenoids electrically connected with their coils and with the said interior contact and a supply-main having one terminal connected with the solenoids 95 and the other connected with said conductor within said solenoids, substantially as set forth.

9. The combination of the driven rotary shaft, the cutting-tool carried by said shaft, 100 power devices for imparting a continuous rotation to the shaft, and a series of successively-acting electromagnets supplemental to the aforesaid power devices and adapted to move said shaft longitudinally to feed the 105 cutting-tool forward from one end of its path to the other, substantially as set forth.

10. The combination of the shaft, the cutting-tool mounted at one end of said shaft, power devices arranged axially about and adapted to continuously rotate said shaft, and a series of successively-acting electromagnets arranged on the opposite side of said power devices from the cutting-tool and adapted to continuously move the said shaft and tool 115 longitudinally of said power devices while being rotated by said devices, substantially as set forth.

11. The combination of the rotary cutting-tool, the electromagnetic motor having two 120 or more magnets adapted to be successively energized to move said tool longitudinally, and a rotary electric motor supplemental to said motor for continuously rotating said tool, substantially as set forth.

12. The combination with the longitudinally-moving cutting-tool, of the series of two or more solenoids, a core arranged within the

solenoids and connected with said tool, each solenoid having one terminal connected with a contact in the path of a contact carried by the core, a conductor arranged within the solenoids parallel to the core and in the path of a contact carried thereby, and a supply-main having one terminal connected with the solenoids and the other terminal connected with the

last said conductor within the solenoids, substantially as set forth.

In testimony whereof I affix my signature in presence of two witnesses.

HENRY H. BLISS.
